UNITED STATES PATENT OFFICE.

SAMUEL LEONARD TRUEBLOOD, OF KENOVA, WEST VIRGINIA, ASSIGNOR OF THREE-EIGHTHS TO GEORGE McDONALD AND JOHN T. INGRAM, OF PARKERSBURG, WEST VIRGINIA.

CAR-COUPING.

SPECIFICATION forming part of Letters Patent No. 717,475, dated December 30, 1902.

Application filed May 20, 1902. Serial No. 108,241. (No model.)

To all whom it may concern:

Be it known that I, SAMUEL LEONARD TRUEBLOOD, a citizen of the United States, residing at Kenova, in the county of Wayne and 5 State of West Virginia, have invented a new and useful Car-Coupling, of which the following is a specification.

The invention relates to improvements in car-couplings.

10 The object of the present invention is to improve the construction of car-couplings of the Janney type and to provide a simple, inexpensive, and efficient one of great strength and durability, capable of automatically coupling when two cars come together and adapted to be set for uncoupling, to obviate the necessity of a person going between cars to uncouple them or of holding the locking-pin in 15 an elevated position to permit cars to uncouple.

Furthermore, the invention has for its object to provide a car-coupling having means for enabling the knuckle to be opened from the side or top of a car or the platform of a 25 coach, to arrange the car-coupling for automatic coupling, and to avoid going between cars to open the knuckle.

The invention consists in the construction and novel combination and arrangement of 30 parts hereinafter fully described, illustrated in the accompanying drawings, and pointed out in the claims hereto appended.

In the drawings, Figure 1 is a vertical sectional view of a car-coupling constructed in accordance with this invention. Fig. 2 is a horizontal sectional view of the same. Fig. 3 is a detail perspective view of the locking-pin. Fig. 4 is a similar view of the knuckle. Fig. 5 is a detail view illustrating another 40 construction for actuating the knuckle to open the same.

Like numerals of reference designate corresponding parts in all the figures of the drawings.

45 I designates a draw-head designed to be provided with a shank or draw-bar of the ordinary construction and to be secured to a car, locomotive, or the like in any desired manner, and the said draw-head is provided 50 at one side with suitable eyes for the recep-

tion of a knuckle-pin 2, and it has its other side 3 extended a considerable distance to form an outwardly-extending guide-arm adapted, should two draw-heads be slightly out of alignment, to guide them into engagement with each other. The guide-arm or side 3 is set at an angle, as shown, and it may be of any desired length to secure the necessary guiding action.

The knuckle-pin 2 pivots a knuckle 4 to the draw-head, and the latter is provided with an approximately U-shaped arm 5, composed of two sides or portions arranged at an angle to each other. One side or portion of the arm extends rearward or inward from the eye of the knuckle and the other side or arm is disposed approximately transversely of the draw-head and is arranged in a transverse opening or passage 6, which extends from the center of the draw-head through the side at 70 which the knuckle is pivoted. The transversely-disposed portion of the arm 5 of the knuckle is slightly curved, as shown, and when the knuckle is closed, as illustrated in Fig. 2 of the draw-head, it fits against the front wall of the transverse openings 6, and as the arm of the knuckle is arranged between the solid side portion 7 of the draw-head and a vertically-movable locking-pin 8, it will be apparent that it cannot become 75 detached from the draw-head should the knuckle-pin 2 break, and that by this arrangement the said knuckle-pin is relieved of strain and is prevented from breaking.

The vertically-movable locking-pin is 85 mounted in a suitable opening of the draw-head, and it is provided at its upper end with a suitable enlargement or head 9, having an eye or opening adapted to be connected with suitable mechanism for enabling the locking-pin to be raised from the top or side of a car or the platform of a coach without going between cars. The lower portion 10 of the locking-pin is recessed or cut away and is provided with a curved face, as clearly shown in 90 Fig. 3, to permit the arm of the knuckle to swing outward when the locking-pin is raised sufficiently to carry an upper engaging portion or shoulder 11 out of engagement with the arm of the knuckle. The engaging por- 100

tion or shoulder, which abuts against the outer side of the rearwardly-extending portion of the arm of the knuckle when the latter is closed, may be of any desired size and area to secure the necessary strength, and when the locking-pin is raised it is supported in such elevated position by a pivoted supporting device 12 to maintain the upper shoulder or engaging portion 11 out of engagement with the arm of the knuckle to permit the latter to open freely and allow coupled cars to separate. The supporting device, which is secured to the locking-pin by a suitable fastening device 13, has its upper end perforated for the reception of the same, and it is arranged within a recess 14, which forms a vertical shoulder or stop to limit the outward swing of the supporting device 12. When the knuckle is closed, the pivoted supporting device is arranged in a horizontal position upon the arm of the knuckle, as clearly shown in Fig. 1 of the drawings, whereby when the locking-pin is raised the pivoted supporting device will automatically swing outward to a vertical position and rest upon the arm of the knuckle, and thereby hold the locking-pin in its elevated position. The knuckle is then adapted to be opened, and when it closes the inward movement of the arm will automatically swing the pivoted supporting device inward and permit the locking-pin to fall and carry its shoulder or engaging portion into engagement with the arm of the knuckle. In practice the vertically-movable locking-pin will be connected with an arm of a transverse rock-shaft, which will be provided at the side of the car with an arm or handle, and in uncoupling cars it will only be necessary for the operator to partially rotate the shaft, and this may be quickly done by a person walking along one side of the train without going between the cars. The locking-pin may be supported in such elevated position while the cars are together, and it may be left in such position to permit the cars to be separated at any future time.

The transversely-disposed portion of the arm of the knuckle is provided with an inclined lower face 15, and the vertically-movable locking-pin is provided at its lower portion with means for engaging the inclined face 15, whereby the locking-pin is adapted to kick the knuckle open to arrange it for automatic coupling or to start the knuckle to facilitate the operation of uncoupling. The means for engaging the inclined face 15 of the arm of the knuckle may be constructed in a variety of ways; but it preferably consists of a roller 16, located normally a sufficient distance below the arm of the knuckle to permit the locking-pin to be raised and set for uncoupling without carrying the antifriction-roller 16 into engagement with the inclined face 15. In other words, the locking-pin has sufficient play to enable it to be set for uncoupling without kicking the knuckle open. When the locking-pin is raised to the

limit of its movement, the antifriction-roller is carried into engagement with the inclined face 15 of the arm of the knuckle and the latter is open; but it is not necessary to lift the locking-pin to this extent to simply set it for automatic uncoupling. This is a decided advantage, as the two operations may be effected either simultaneously or separately. The antifriction-roller 16 is mounted on a suitable pivot or spindle 17 of a plate 18, which is secured to the lower portion of the locking-pin in a suitable groove or recess 19 thereof; but it may be mounted on the locking-pin in any other suitable manner, and the antifriction-roller can be dispensed with and a fixed projected portion be provided for actuating the knuckle. It will be necessary when such a construction is employed to keep the parts thoroughly lubricated in order to secure the best results; but an antifriction-roller will be found preferable. The inclined face 15 may be flat, or a rounded inclined face 20, as illustrated in Fig. 5, may be employed, and a correspondingly-grooved antifriction roller or wheel 21 may be employed, or the rounded inclined face may be arranged to operate in connection with an antifriction-roller 16, as shown in Fig. 3. The transversely-disposed portion or side of the arm of the knuckle is provided at its end with a projecting lug 22, forming a shoulder for engaging the lower portion of the locking-pin to limit the opening movement of the knuckle and prevent the arm of the knuckle from being swung outward beyond the pivoted supporting device.

It will be seen that the car-coupling is simple and comparatively inexpensive in construction, that it possesses great strength and durability, and that the knuckle-pin is relieved of strain and the knuckle effectually prevented from leaving the draw-head should the knuckle-pin become broken. It will also be clear that the car-coupling is capable of coupling automatically when two cars come together, and that it may be readily operated to effect the operation of uncoupling without going between cars. It will also be apparent that the knuckle may be opened from the side of the car, and that numerous accidents resulting from attempts to open the knuckle while a car is in motion or to maintain an ordinary locking-pin in an elevated position under such conditions will be effectually prevented. Furthermore, the car-coupling will be found of the greatest advantage in handling cars in yards while making up trains or distributing cars, and that in all such operations it will obviate the necessity of a train-hand exposing himself to danger while manipulating the car-coupling.

What I claim is—

1. The combination with a coupling-head, and a knuckle pivotally supported therein, the said knuckle having the rearwardly-projecting tail having an inclined lower edge, of a vertically-movable locking-block, and a

roller mounted in said locking-block below the tail of the knuckle and adapted to engage the said lower inclined edge of the tail of the latter, substantially as described.

- 5 2. In a car-coupling, the combination with a draw-head, and knuckle pivoted therein and provided with a tail having an inclined lower edge, of a vertically-movable block for locking the knuckle in its closed position, a 10 roller mounted in the lower portion of said block and engaging the inclined lower edge of the knuckle-tail, means for suspending the locking-block in an unlocked position and for retaining it so suspended until released 15 by the knuckle-tail in the outward opening movement of the latter, substantially as described.
3. In a car-coupling, the combination of a draw-head, a pivoted knuckle, a locking-pin, 20 and a supporting device pivoted to the locking-pin and arranged in a horizontal position upon the arm of the knuckle when the latter is closed and adapted to swing to an upright position when the locking-pin is raised, 25 said locking-pin being provided with means for limiting the outward swing of the supporting device, and the latter being arranged to be swung inward to the said horizontal position by the inward movement of the arm of 30 the knuckle, substantially as described.

4. In a car-coupling, the combination of a draw-head, a pivoted knuckle, a locking-pin provided with a recess or cut-away lower portion, and having an upper shoulder or en- 35 gaging portion adapted to abut against the arm of the knuckle, said locking-pin being

also provided at the shoulder or engaging portion with a recess 14, forming a stop-shoulder, and a supporting device pivoted at its upper end in the recess 14 and arranged in a horizontal position upon the arm of the knuckle when the latter is closed and adapted to swing to an upright position when the locking-pin is raised, said supporting device having its outward movement limited by the shoulder 45 of the recess 14, and arranged to be swung inward to the said horizontal position by the inward movement of the arm of the knuckle, substantially as described.

5. In a car-coupling, the combination of a 50 draw-head, a knuckle provided with an arm having an inclined face, and a locking-pin provided with an antifriction-roller arranged to engage the inclined face to open the knuckle, substantially as described. 55

6. In a car-coupling, the combination of a draw-head, a pivoted knuckle provided with an arm having an inclined lower face, a locking-pin, a pivoted supporting device mounted on the upper portion of the locking-pin and 60 arranged to rest upon the arm of the knuckle, and an antifriction roller or wheel mounted on the lower portion of the locking-pin and arranged to engage the inclined face of the arm of the knuckle, substantially as described. 65

In testimony that I claim the foregoing as my own I have hereto affixed my signature in the presence of two witnesses.

SAMUEL LEONARD TRUEBLOOD.
